CLAIM

The ornamental design for an over-cab rack, as shown and described.

DESCRIPTION

FIG. 1 is a perspective view of the first embodiment of the over-cab rack, showing my new design positioned on top of a vehicle,

FIG. 2 is another perspective view of the same,

FIG. 3 is a rear view of the same,

FIG. 4 is a side view of the same,

FIG. 5 is another perspective view of the same,

FIG. 6 is a top view of the same,

FIG. 7 is a perspective view of the second embodiment of the over-cab rack, showing my new design positioned on top of a vehicle,

FIG. 8 is another perspective view of the same,

FIG. 9 is a rear view of the same,

FIG. 10 is a side view of the same,

FIG. 11 is another perspective view of the same; and,

FIG. 12 is a top view of the same.

The broken lines are for the purpose of illustrating environmental structure and form no part of the claimed design.

1 Claim, 10 Drawing Sheets
